Primary Examiner—Paula A. Mortimer

Attorney, Agent, or Firm—Browdy and Neimark

[57] **CLAIM**

The ornamental design for a “weighted glove”, as shown and described.

DESCRIPTION

FIG. 1 is a perspective view of a weighted glove showing my new design;

FIG. 2 is a front elevational view thereof;

FIG. 3 is a rear elevational view thereof;

FIG. 4 is a left end elevational view thereof;

FIG. 5 is a right end elevational view thereof;

FIG. 6 is a top plan view thereof;

FIG. 7 is a bottom plan view thereof; and,

FIG. 8 is a perspective view thereof.

The broken line showing of the human form in FIG. 8 is for illustrative purposes only and forms no part of the claimed design.
